US0D1034373S

(12) **United States Design Patent** (10) **Patent No.:** **US D1,034,373 S**
(45) **Date of Patent:** **** Jul. 9, 2024**

(54) **COWL FOR A VEHICLE**

(71) Applicants: **Zhejiang ZEEKR Automobile Research & Development Co., Ltd., Ningbo (CN); Zhejiang Geely Holding Group Co., Ltd., Hangzhou (CN)**

(72) Inventor: **Asok George**, Gothenburg (SE)

(73) Assignees: **Zhejiang ZEEKR Automobile Res. & Dev. Co., Ltd., Ningbo (CN); Zhejiang Geely Holding Group Co., Ltd., Hangzhou (CN)**

(**) Term: **15 Years**

(21) Appl. No.: **29/834,772**

(22) Filed: **Apr. 14, 2022**

(51) LOC (14) Cl. **12-16**

(52) U.S. Cl.

USPC **D12/192**
